BED SHEET OR SIMILAR ARTICLE OF BED LINEN

Emeric Kanitz, Paris, France, assignor to Cannon Mill's
Company, Kannapolis, N.C., a corporation of North Carolina

Filed Nov. 13, 1967, Ser. No. 9,375

Term of patent 14 years

(Cl. D92—26)

The essential features of my design reside in the design on the border.

I claim:

The ornamental design for a bed sheet or similar article of bed linen, substantially as shown and described.
